CLAIM

The ornamental design for a shoe, as shown and described.

DESCRIPTION

FIG. 1 is a rear perspective view of a shoe showing my new design;

FIG. 2 is a side view thereof;

FIG. 3 is a rear view thereof;

FIG. 4 is an opposite side rear perspective view thereof; and, FIG. 5 is an opposite side view thereof.

The uneven-length broken lines immediately adjacent to the shaded area define the bounds of the claimed design and form no part thereof. The even-length broken lines represent stitching that forms no part of the claimed design. The uneven-length broken line showing the triangle shaped element forms no part of the claimed design. The uneven-length broken lines depicting the remainder of the shoe form no part of the claimed design.
